SAFETY DEVICE FOR PRESSES OR
STAMPING MACHINES

Joseph J. Wargas, Astoria, Long Island, N. Y.

Application December 3, 1946, Serial No. 713,781

3 Claims. (Cl. 74—615)

1

This invention relates to safety devices for presses and stamping machines.

It is known to provide automatically operated safety gates or guards which are interposed between the operator and the descending punch for the purpose of brushing the operator's hand out of the way. Such known safety devices suffer from the following disadvantages: (1) They are primarily designed for use with machines where the work does not require handling during the entire stamping operation, and hence do not permit manipulation of the work by the operator over substantially the entire cycle of stamping operations; (2) they are so constructed that the initial adjustment can be tampered with by the operator, and for this reason cause injury to the operator's hands; and (3) in the case where safety devices swing in an arcuate path they enable the operator's fingers to be caught between the stamping parts for certain positions of the operator's hands.

The present invention is a safety device which overcomes the foregoing disadvantages. It is primarily designed for use in a foot-operated press where the work is small and must be held down by the hand of the operator at all times while the ram is descending and until the punch operation is completed.

More specifically, the safety device of the invention comprises a sliding metallic block-like guard which moves horizontally in response to movement of the punch and slides within a pair of spaced guides. This guard is positioned in a plane immediately above the die and is provided at its end nearest the stamping parts with a pair of vertically arranged but horizontally spaced plates which enable the punch to descend into the space between the plates. As the spaced plates approach the stamping parts during the descending position of the punch, they brush away the fingers of the operator from the location between the stamping parts. The dimensions of the plates and the limit of movement of the guard is such as to permit the fingers of the operator to hold a piece of work on both sides of the moving plates without danger to the fingers by the descending punch. The sliding guard is so arranged that it cannot be tampered with or adjusted from the front of the machine which faces the operator, and hence obviates a known cause of injury to the operator.

A more detailed description of the invention follows in conjunction with a drawing, wherein

Fig. 1 is a front elevation of a press provided with the safety feature of the invention;

2

Fig. 2 is a side elevation of the press of Fig 1; and

Fig. 3 is a perspective view of the sliding guard showing the details of mounting the same.

Referring to the drawing in more detail, wherein the same parts are represented by the same reference numerals throughout the figures, Figs. 1 and 2 show a treadle-operated press or stamping machine having a bed 1, a flat base 2 adapted to rest upon the bed, and stamping parts composed of a die 3 and a punch or ram 4. The punch 4 forms part of a punch press of conventional construction and is caused to descend in response to movement of a treadle, in turn, linked to member 5.

The safety device of the invention comprises a metallic block 6 which is freely slideable in a horizontal direction within a pair of guides 7, 7, in turn, mounted and supported by a vertical metallic plate 8 secured at its base to the bed of the press by bolts 10. At the front end of the block 6 are two vertical and physically parallel plates 9, 9 which are spaced from each other a sufficient distance to enable the punch 4 to pass therebetween in its descending travel. It should be noted that the block 6 is positioned slightly above the die 3. Passing through the block 6 at a location intermediate its ends is a pin 11 which engages the sides of a slot 12 arranged longitudinally in a lever 13. This lever is pivotally mounted at 14 to the stationary frame of the press. The upper end of lever 13 is provided with a cam surface 15 which engages cam surface 16 of the descending portion of the press. A spring 17 is fastened at one end to a screw 18 at the upper end of the lever 13 and is fastened at its other end to a screw 19 on the stationary frame of the press, thus exerting a force on lever 13 which tends to maintain the lever 13 in the position shown in Fig. 1.

The press shown in Figs. 1 and 2 is designed for use in stamping small parts, such as the prong of a buckle to the buckle itself. A buckle prong to be stamped is shown upon the die 3 in Fig. 1 and is labeled 20. During the stamping operation, the buckle is held by the fingers of the operator on opposite sides of the die so that it maintains a desired position relative to the curved end of the buckle prong while the ram or punch descends. It is important during this stamping operation that the fingers of the operator be protected from danger and prevented from being caught between the punch 4 and the die 3 or the work.

In operation, as the punch descends in response to the foot pressure of the operator upon the

treadle, the descending cam 16 will force the upper end of the lever 13 to the left (note Fig. 1). Since lever 13 is pivoted at 14, the lower end of this lever 13 will travel to the right and, through the medium of pin 11, slide the guard 6 to the right toward the stamping parts. The vertical plates 9, 9 are curved at their ends and brush away the fingers of the operator if they should be positioned between the punch 4 and the die 3. The spacing between the plates 9, 9 enables the punch 4 to descend and contact the work. When the foot treadle is released, the punch will be raised and permit the lever 13 to assume its original position shown in Fig. 1. As the punch ascends, the guard 6 will move to the left. It will thus be seen that there is a reciprocating sliding motion on the part of guard 6 which is automatic in response to movement of the punch.

The position of guard 6 and the dimensions of the elements 9, 9 and 13 are so related that the fingers of the operator are protected from injury during the descending travel of the punch 14, while permitting the fingers of the operator's right hand to straddle the guard and hold the work safely.

The mounting of the safety guard plate from the rear by means of bolts 10, 10 discourages tampering with the adjustment by the operator.

What is claimed is:

1. In a press having a punch intermittently operating above a stationary die, a safety guard positioned above said die, means for reciprocating said guard horizontally in a straight line above said die for protecting the fingers of the operator from injury, a pair of horizontally spaced hollow guides enabling said guard to slide therein, a vertical metallic mounting plate supporting said guides from the rear, and means in the rear of said mounting plate for securing the same to said press, said guard comprising a pair of vertical plates located at the end nearest said punch and die, said pair of vertical plates being parallel and horizontally positioned apart a distance sufficient to enable the punch to descend therebetween, the movement of said guard being such as to cause said pair of plates to assume a position on both sides of said punch as it nears said die.

2. In a foot operated press having a stationary die and a movable coacting punch, the combination with a guard reciprocating in a straight line

at right angles to the motion of said punch, said guard being positioned in a line slightly above said die, a pair of spaced parallel metallic plates fastened to the end of said guard nearest said die, said plates being spaced apart a sufficient distance to enable said punch to descend therebetween and contact the work on the die, the movement of said guard being such as to cause said plates to assume a position on both sides of said punch as it nears said die, means for holding said guard away from said die when said punch is not in operation, and means responsive to the operation of said press for moving said guard toward said die and punch.

3. In a foot operated press having a stationary die and a movable coacting punch, the combination with a guard reciprocating in a straight line at right angles to the motion of said punch, said guard being positioned in a line slightly above said die, a pair of spaced parallel metallic plates fastened to the end of said guard nearest said die, said plates being spaced apart a sufficient distance to enable said punch to descend therebetween and contact the work on the die, the ends of said plates being curved, a lever pivoted at a location intermediate its ends and having one end engaging said guard by means of a pin and slot arrangement, a spring fastened to the other end of said lever and exerting pressure on said lever in such direction as to hold said guard away from said die when said press is not in operation, and means on said press for opposing the pressure of said spring and for moving said lever in a direction opposite to said first direction to cause movement of said guard toward said die in response to the operation of said press.
